29. G. E. MOLYNEUX
APPARATUS FOR INSPECTING THE INTERIORS OF SHOES
AND REMOVING TACKS THEREFROM
Filed Feb. 10, 1923

1,707,989

UNITED STATES PATENT OFFICE.

GEORGE E. MOLYNEUX, OF BAYONNE, NEW JERSEY, ASSIGNOR TO UNITED SHOE MACHINERY CORPORATION, OF PATERSON, NEW JERSEY, A CORPORATION OF NEW JERSEY.

APPARATUS FOR INSPECTING THE INTERIORS OF SHOES AND REMOVING TACKS THEREFROM.

Application filed February 10, 1923. Serial No. 618,367.

This invention relates to apparatus for use in inspecting the interiors of shoes to discover tacks therein and for removing such tacks from the shoes when discovered.

5 In the manufacture of shoes of substantially all kinds tacks are employed as temporary fastening means for holding the soles or innersoles to the last and for holding the uppers temporarily in lasted position upon 10 the soles or innersoles. These tacks are driven through the innersole or through the upper and innersole into the wood of the last, the innersole tacks, in the case of a McKay shoe, being driven through openings provided in 15 the iron plate which covers the bottom of the last. The tacks for holding the innersole are usually four in number, one being driven through the innersole near the toe, one near the ball, one in the shank, and one in the heel- 20 seat. The tacks for holding the lasted upper in place are driven through the bottom portion of the upper and into the margin of the sole except at the toe where the upper is usually held in place by means of a wire held by 25 anchor tacks driven through the upper and into the sole near the ends of the tip line. After the upper has been permanently secured to the innersole the operation of removing the innersole tacks and the lasting tacks is per- 30 formed. Sometimes, however, the head of an innersole tack is broken off, rendering it impracticable to remove the tack at that time and occasionally a tack is overlooked. With regard to the lasting tacks, these are some- 35 times broken by the sewing needle or by the upper trimming machine so that the points of them remain in the shoe until the shoe is completed and reaches the packing room. When the last is pulled the broken tacks are 40 sometimes drawn through the sole and removed with the last. Frequently, however, they remain in the shoe with their points projecting into the interior thereof. Before being packed the shoes are inspected to ascer- 45 tain whether there are any such tacks in the shoe and if any are found they are cut off flush with the surface of the innersole. If the tacks are undiscovered in the packing room and the shoe reaches the retailer, they are 50 likely to cause serious injury to a person who tries the shoe on. Sometimes the tacks are so placed that while a person has no difficulty in getting the shoe on, it is found impossible to remove the shoe without tearing the stocking or injuring the foot, and the 55 shoe has to be cut open and destroyed to remove it. Some of these tacks, particularly broken anchor tacks and the toe tack of the innersole, are located well toward the toe of the shoe and their detection and removal by 60 any means heretofore provided are particularly difficult and uncertain.

An object of this invention is to provide improved apparatus for inspecting shoes either in the factory or at the retail store to 65 ascertain whether such tacks are present in the shoe, by rendering them visible to the operator, and means for removing them and also for rendering them visible to the operator during the operation of removal. 70

A feature of the invention consists in a lamp mounted in fixed position and reflecting means located in fixed position at the rear of the lamp with its reflecting surface next thereto, the arrangement being such that 75 the shoe may be placed over the lamp and reflecting means, the reflecting means producing a reflected image of the lighted interior of the shoe for observation by the operator. Preferably a shield is provided be- 80 tween the lamp and the reflecting means to cut off direct radiation from the lamp to the reflecting means. In order that the shoe may be moved easily to present all interior parts of its toe to the operator's line of vision 85 through the reflector, the illustrated lamp and reflecting means have been assembled compactly and in such a manner that the lamp is located in the angle between the visual rays incident to and those reflected from the re- 90 flector. It should be noted in this connection that this construction affords a maximum of illumination, the lamp being relatively near the object to be illuminated and also that the reflecting means may be located in 95 close proximity to any marginal portion of the shoe without there being any intervening obstruction, as would be the case if the lamp were below or at either side of the reflecting means. Conveniently the lamp may be 100 electric and may be provided with a switch which is closed by means arranged in the path of the shoe as it is brought into position over the lamp so that the lamp will be turned on

as an incident to presenting the shoe for inspection.

Another feature of the invention consists in tack removing means mounted in such a fixed position that the shoe may be placed over it and manipulated with respect thereto to present a tack to the removing means, means for illuminating the interior of the shoe and the removing means, means for reflecting the image of the removing means and adjacent portions of the shoe to the operator's eye to enable the tack in the shoe to be seen and located with respect to the removing means, and means for operating the tack removing means. As shown, the tack removing means comprises a pair of cutting nippers one jaw and handle of which are fixed in position and the other jaw and handle movable to cause the jaws to operate to cut off a tack. Since the operator's hands are both occupied in holding and manipulating the shoe it is desirable to arrange the nippers for operation by a lower limb of the operator. Accordingly, as shown, the movable handle of the nipper is arranged for operation by means of a foot lever or treadle to close the jaws. Preferably also a switch for controlling the light is arranged to be operated by movement of the connections between the movable handle and the treadle so that a preliminary movement of the treadle insufficient to close the jaws will operate to close the switch and turn on the light, the nipper jaws being operated by further movement of the treadle.

While the toe portion of the shoe is in position over the nippers it is desirable to enable the operator to inspect the rear portion of the interior of the shoe without substantially changing the position of the shoe, direct vision of this portion of the shoe while in this position being obscured by the presence of the nippers. Accordingly a mirror is provided for enabling the operator to view the rear portion of the shoe while the shoe is in position with its forepart over the nippers.

These and other novel features and details of the arrangement of the parts will appear more fully from the following detailed description when read in connection with the accompanying drawings and will be pointed out in the appended claims.

In the drawings:

Fig. 1 is a side view of apparatus located on the right-hand side of the machine for facilitating the inspection of the interior of a shoe to discover tacks therein if there are any;

Fig. 2 is a side view of apparatus on the left-hand side of the machine for locating and removing a tack which has been discovered;

Fig. 3 is a diagram of the electric circuits used in the apparatus;

Fig. 4 is a diagrammatic view explaining

the use of the apparatus for inspecting the rear portion of the shoe; and

Fig. 5 is a perspective view of the nippers and the operating means therefor.

In the drawings, a support or column 2 is shown which may be of any convenient height to accommodate the operator in either a standing or sitting position. On the column 2 is a hollow horizontal projection 4 extending toward the operator's position which is at the end of the projection facing the column. On the projection 4 at the operator's right is arranged the apparatus and mechanism shown in Fig. 1 which comprises a low voltage electric lamp 6, current for which is supplied by a transformer 8 located on the top of the column as shown in Fig. 2, the transformer being supplied with alternating current from the commercial lighting circuit by a lamp cord 10. The lamp 6 is mounted on a bracket 12 secured at 14 to the projection 4 and is shielded by an opaque, cylindrical sleeve 16 frictionally held on the lamp socket and cut away at its front portion so that the lamp may emit light downwardly and forwardly. At the rear of the shield 16 is mounted a reflecting means 18 which, as shown, is in the form of a totally reflecting prism mounted in a clip 20 which is secured at 22 to the lamp bracket 12. A right angle prism is, of course, more efficient as a light reflector than a plane mirror. When a shoe is placed over the lamp and reflecting means, as shown in Fig. 1, the light from the lamp will illuminate the entire inner surface of the forepart of the sole and all portions of it may be seen by the operator with his eye located, as shown, in the line of the reflected rays.

In order that the lamp 6 may be energized only when needed, a switch is arranged to close the secondary circuit of the transformer through the lamp as an incident to presentation of the shoe in position to be inspected. The switch comprises a rotary element 24 mounted by a bolt 25 on an insulating block 26 secured to the projection 4. The bolt 25 is electrically connected to the secondary circuit of the transformer. The rotary element 24 has inserted in its periphery a block of insulating material 28 (Fig. 3), and a brush 30 in the form of a spring is arranged on the block 26 to engage the periphery of the rotating element 24. When the element 24 is in such position that the insulating material 28 engages the brush 30 the lamp is turned off and when the element 24 is turned so as to bring the brush in contact with other portions of the periphery of the element 24 the lamp is turned on. The element 24 is normally held by a weighted arm 32 in its off position, and when it is desired to inspect the shoe, the shoe is brought into engagement with the arm 32 in its movement to position it over the lamp and reflecting means, and the element 24 is thereby rotated and the lamp 130

turned on. Other portions of the shoe bottom than the forepart may be inspected by moving the shoe longitudinally while the operator's eye remains in the same position 5 with respect to the reflecting means 18. Since the segment 28 occupies only a small portion of the periphery of the rotating element 24, the operating arm 32 may be moved through a wide range of positions during manipulation 10 of the shoe without affecting the operation of the light. When, however, the shoe is removed and the arm 32 is allowed to drop into a substantially vertical position, the lamp is automatically turned off.

15 After a shoe has been inspected, if no tacks are found it is passed along and another shoe inspected. Of course in a very large majority of shoes no tacks will be found as they occur only accidentally. When, however, a tack 20 is discovered the shoe is transferred to the opposite side of the projection 4 where the apparatus shown in Fig. 2 is located. This apparatus consists of a lamp 50 similar to the lamp 6 and connected in parallel therewith 25 in the secondary circuit of the transformer 8. The lamp 50 has its socket mounted on a bracket 52 which is pivoted to an ear on the projection 4 by a screw 56 which is provided with a friction washer so that the bracket 30 will remain in any position to which it is swung about the screw as a pivot. If desired the screw 56 may be so adjusted that the bracket 52 will turn freely upon it and a spring 60 provided between the bracket and 35 the projection 4 so as to hold the lamp normally in a forward position. The lamp will then be pushed back when it comes in contact with the upper of a shoe at the throat, as indicated in Fig. 2. The lamp 50 is provided with a shield 58 similar to the shield 16 to intercept rays of light from the lamp except those directed forwardly and downwardly. Back of the lamp 50 and shield 58 a reflecting means 62 is located. This preferably 40 is in the form of a totally reflecting prism, because of the superior efficiency of such reflecting means over an ordinary mirror. The prism 62 is mounted in a metal clip 63 which is secured by screws 64 to an arm 45 pivoted at 68 to an ear on the projection 4 so that it may be swung in a substantially vertical plane extending transversely of the projection into and out of the operative position shown. Beneath the lamp is arranged a 50 pair of cutting nippers the jaws 70 of which are formed and arranged for the purpose of cutting off a tack or the like flush with the surface from which it projects. One of the handles of the nippers has an upward and 55 forward extension 72 which is secured by screws 74 to the projection 4. The other handle 73 of the nippers is, of course, movable to operate the jaws 70, and in the construction shown is arranged to be operated by a 60 foot treadle 75. The handle 73 has secured 65 thereto, in any suitable manner, a flexible connection 76 such as stranded wire cable which is led first over a pulley 78 mounted on the extension 72 of the fixed handle of the nippers and then over a pulley 80 mounted 70 on a lateral extension of the projection 4. This end of the cable 76 is secured to one arm 82 of a bell crank lever which is pivoted at 84 to an ear on the projection 4. The other arm of the lever extends through an opening 75 to the interior of the projection 4 and has connected to its a cable 86 which is led rearwardly over a pulley 88 and thence downwardly to the floor where it is connected to the treadle 75 so that depression of the treadle 80 will effect a pull on the cable and, through the connections described, move the handle 73 toward the fixed handle to operate the nipper jaws 70. Movement of the arm 82 of the bell crank lever is utilized to operate a 85 switch for the lamp 50. The switch, as shown in Fig. 2, consists of two spring strips 90, 92 secured at their forward ends to an insulating block 94. The strips have contact points at 96 which are normally separated. On the 90 strip 90 is a contact piece 98 overhanging the end of the block 94 and disposed in the path of movement of the arm 82, the end of the arm and the contact piece 98 being relatively 95 cam shaped to cause the strip 90 to be raised and the points 96 brought in contact, any excess movement of the strip 90 being permitted by the resiliency of the strips 90, 92. The switch is arranged to be operated by a preliminary movement of the arm 82 by the 100 treadle insufficient to close the nipper jaws, so that the lamp 50 will be lighted automatically as an incident to the operator's placing his foot on the treadle preparatory to removing a tack that has been discovered in a shoe. 105

When the operator, by the use of the inspection apparatus at the right-hand side of the machine, discovers a tack in a shoe, he places the shoe over the nippers 70 and, placing his foot on the treadle, turns on the lamp 110 50, thereby causing the nippers and the interior of the shoe to be illuminated; then, viewing the tack and the nippers by means of the prism 62, he manipulates the shoe 115 relatively to the nippers to position the discovered tack between the jaws and then operates further the treadle to cause the nippers to sever the tack. The nipper jaws may be magnetized, permanently or electrically, so that the severed portion of the tack will 120 cling to the jaws until the shoe is removed and may then be brushed off, thus ensuring that the severed tack point will not remain in the shoe.

At this stage of the operation the operator 125 may wish again to inspect the rear portion of the shoe while the shoe is still pointed toward him and over the nippers and without returning the shoe to the other side of the machine. Direct vision of the rear por- 130

tion of the shoe is obscured by the nipper handles and the prism 62, but, by moving the shoe slightly to cause its rear interior portion to be illuminated and directing his eye 5 toward a mirror 100 adjustably mounted at 102 to a bracket 104 secured by a screw 106 to the projection, the operator may secure an unobstructed view of the rear portion of the shoe, the prism 62 being swung on its 10 pivot out of the way if that is desirable. This operation is shown diagrammatically in Fig. 4. The mirror 100 and its bracket 104 are adjustably held so that the mirror may be placed in various positions and at any 15 desired angle best suited for viewing the work in hand.

The electrical connections of the apparatus, as shown, are represented diagrammatically in Fig. 3, in which it will be seen 20 that the lamps are of the "single contact" type, one terminal, the socket, being "grounded" to the machine frame. The primary coil of the transformer, which is connected to the commercial lighting circuit, is represented at 110, and the secondary coil, one side of which is grounded, is represented at 112. Wires lead from the ungrounded side 25 of the secondary coil 112 to the respective switches of the two lamps 6 and 50 and 30 from the switches to the "live" terminals of the respective lamps. The secondary voltage being low, for example 6 volts, this arrangement does not endanger the apparatus or the operator and is much simpler and 35 more convenient than a two-wire circuit would be, though of course such a circuit could be employed if desired. The capacity of the transformer may be such that it will 40 effectively light only one lamp at a time since, in the normal use of the apparatus, the automatic switch ensures that when one lamp is turned on the other will be turned off.

Having thus described my invention, what 45 I claim as new and desire to secure by Letters Patent of the United States is:

1. In an apparatus of the class described, the combination of a lamp for illuminating the toe portion of the interior of a shoe, and 50 a reflector to form a visible image of the interior toe portion thereof arranged at the rear of the lamp and having its reflecting surface next thereto.

2. In an apparatus of the class described, 55 the combination of a lamp for illuminating the interior of a shoe held with its toe toward the operator, a reflector so constructed and arranged that the lamp is included between the visual rays incident to and those reflected from the reflector to form a visible image of the interior of the shoe, and a screen between the lamp and the reflector to cut off direct radiation of light from the lamp to the reflector.

3. In an apparatus for use in removing

tacks from the interiors of shoes, the combination of a support, tack removing means secured in fixed relation to the support so that a shoe may be placed over said removing means and manipulated with respect thereto, and a lamp for illuminating the removing means and the interior of the shoe. 70

4. In an apparatus for use in removing tacks from the interiors of shoes, the combination of a support, tack cutting means on the 75 support arranged so that a shoe may be placed over it and manipulated with respect thereto for the removal of tacks projecting into the interior of the shoe, and means for rendering the interior of the shoe visible to the operator so that tacks in the shoe may be intelligently directed to the cutting means. 80

5. In an apparatus for use in removing tacks from the interiors of shoes, the combination of a support, a pair of cutting nippers secured in fixed relation to the support so that a shoe may be placed over the nippers and manipulated with respect thereto, a lamp for illuminating the nippers and the interior of the shoe, and means for presenting to the operator's vision an image of the nippers and the interior of the shoe. 85 90

6. In an apparatus for use in removing tacks from the interiors of shoes, the combination of a support, tack cutting means on the 95 support arranged so that a shoe may be placed over it and manipulated with respect thereto for the removal of tacks projecting into the interior of the shoe, manual means arranged for actuation by a lower limb of the operator 100 for operating the cutting means while both his hands are occupied in manipulating the shoe, means for lighting the interior of the shoe, and means for rendering the interior of the shoe visible to the operator so that tacks in 105 the shoe may be intelligently directed to the cutting means.

7. In an apparatus for use in removing tacks from the interiors of shoes, the combination of a support, a tack cutting means on the 110 support arranged so that a shoe may be placed over it and manipulated with respect thereto for the removal of tacks projecting into the interior of the shoe, means for lighting the interior of the shoe, means for rendering the interior of the shoe visible to the operator so that tacks in the shoe may be intelligently directed to the cutting means, manual means for operating the cutting means, and means operated by a preliminary movement of said 115 120 manual means for energizing the lighting means.

8. In an apparatus for use in removing tacks from the interiors of shoes, the combination of a support, a pair of cutting nippers secured in fixed relation to the support so that a shoe may be placed over the nippers and manipulated with respect thereto, a lamp for illuminating the nippers and the interior of the shoe, a switch for controlling the lamp, 125 130

- means for operating the nippers, means operating as an incident to movement of the nipper operating means for closing the switch, and means for forming an image of the illuminated nippers and adjacent portions of the shoe to enable the operator by viewing the image to manipulate the shoe to locate a projecting tack between the nipper jaws.
9. In an apparatus for use in removing 10 tacks from the interiors of shoes, the combination of a support, tack cutting means on the support arranged so that a shoe may be placed over it and manipulated with respect thereto for the removal of tacks projecting into the 15 interior of the shoe, means for operating the cutting means, and means comprising a component part of the tack cutting means for causing the severed tack to remain on the cutting means so that it may be brushed off after 20 the shoe is removed.
10. In an apparatus for use in removing tacks from the interiors of shoes, the combination of a support, a pair of cutting nippers secured in fixed relation to the support so that 25 a shoe may be placed over the nippers and manipulated with respect thereto, and means for operating the nippers, the nippers being magnetized to cause detached portions of tacks to 30 cling to the jaws instead of falling into the shoe.
11. In an apparatus for use in removing tacks from the interiors of shoe, the combination of a support, tack cutting means on the support arranged so that a shoe may be placed over it and manipulated with respect thereto 35 for the removal of tacks projecting into the interior of the shoe, means for lighting the interior of the shoe, and means for rendering the rear part of the interior of the shoe visible to the operator while the shoe is held over the 40 tack cutting means and direct vision of the rear part of the shoe is obscured.
12. In an apparatus for use in removing tacks from the interiors of shoes, a pair of cutting nippers for severing the tacks constructed and arranged to retain the severed portions of the tacks, and means for rendering the interior of the shoe visible to the operator 45 during operation of the cutting nippers.
13. In an apparatus for use in removing 50 tacks from the interiors of shoes, cutting nippers comprising cutting edges for severing the tacks and means for retaining the severed portions of the tacks, and means for rendering the interior of the shoe visible to the operator 55 during operation of the cutting nippers.

In testimony whereof I have signed my name to this specification.

GEORGE E. MOLYNEUX.
